STITCHING MACHINE

Eugene G. Wolf, St. Louis, Mo., assignor to Landis
Machine Company, St. Louis, Mo., a corpora-
tion of Missouri

Application December 7, 1931, Serial No. 579,610

12 Claims. (Cl. 112—36)

The invention relates to stitchers of the type used specially in shoe manufacturing for sewing the soles, to the uppers, and the invention is particularly adopted for use on McKay stitchers.

5 The invention comprises all of the novel features described below and illustrated in the accompanying drawings and claimed herein.

One object of the invention is to make it possible to stitch through the sole and the upper at 10 a point nearer to the breast of the heel than has been possible with lock stitch McKay machines heretofore. I accomplish this object by locating the needle intermediate the planes of the sides of the shuttle whereby only approximately half 15 of the thickness of the shuttle intervenes between the needle and the breast of the heel, whereas previously the entire thickness of the shuttle so intervened and thereby limited the approach of the heel breast to the needle.

20 Another object of the invention is to provide a shuttle and needle assembly in which the shuttle lifts the horn thread loop from the barb of the needle without fraying or otherwise injuring the thread.

25 Other detailed objects of my invention incidental and supplemental to the above-mentioned objects will be apparent from the following specification and the accompanying illustrations, in which—

30 Figure 1 is a front elevation of the machine with a portion of the horn sectioned and showing the parts inside thereof.

Figure 1a shows the needle raised above the position in Figure 1 and pulling the locking thread upwardly.

35 Figure 2 is a side elevation of the machine with a portion of the horn sectioned to illustrate mechanism within the same.

40 Figure 3 is an enlarged detail view of the horn-contained mechanism and corresponds to the showing in Figure 1.

Figure 4 is a horizontal section through the horn taken approximately on line 4—4 of Figure 3.

45 Figure 5 is a horizontal section through the forward portion of the shuttle with the adjacent thread separator also shown.

Figure 6 is a top view of the shuttle.

Figure 7 is a side view of the shuttle.

50 Figure 8 is a top view of some of the mechanism with parts sectioned for clearer illustration.

Figure 9 is a front elevation of the needle, presser foot bar and work feed mechanism drawn on an enlarged scale.

Figure 10 is a side elevation of the same.

The machine stand or frame is indicated at 1 and mounts a head 2 on which the upper operating shaft 3 and mechanism operated thereby are carried. A bracket 4 on frame 1 supports 5 the horn 5 which is freely rotatable about a vertical axis in line with the needle 6 driven by the head mechanism. The needle bar 7 is reciprocated vertically by the cam 8 on the operating shaft 3 through the cam lever 9 connected to the 10 needle bar by a link 10.

The drum-like shuttle 11 has a substantially circular periphery fitting a stationary bearing 12 in which it is oscillated by a cam 13 on the operating shaft 3, which cam moves an offset lever 15 14 having a tooth segment 15 on its lower end meshing with a pinion 16 rigid with a gear 17 which engages teeth 18 on the left-hand periphery of the shuttle 11. Shuttle 11 is hollow and receives a bobbin case 19 and a bobbin 20 20 about which the bobbin thread T is wound. (Figs. 5 and 7.)

The needle 6 may extend into a peripheral groove 21 in shuttle 11, and throughout the arc A (Fig. 7) this groove is widened and deepened 25 as indicated at 22 (Fig. 6) to receive the needle bar 7 as the latter descends, with the shuttle stationary, for the needle to engage the thread L supplied through the horn. At all times the groove 21 receives some portion of the structure 30 comprising the needle and its bar. The peripheral wall of the bobbin case 19 is also grooved somewhat at this point. This grooving of the shuttle and bobbin case permits the needle to be located relatively close to the shuttle axis and the 35 distance from the shuttle axis to the loop taking points 29 is less than would be required if the needle axis were more remote. Hence the shuttle diameter and the length of travel of the shuttle point are reduced accordingly.

40 As the needle ascends, drawing the looped horn thread upwardly (see Figures 1a and 5) the two strands of thread indicated at S are separated by the point 23 of a lever 24 pivoted at 25 (Fig. 2) and operated by a link 26 and a bell crank 27 45 controlled by a cam 28 on the shaft 3. The needle, separator and shuttle cams are so timed that as needle bar 7 is elevated above the position shown in Figure 2, point 23 moves inwardly to separate the strands of the locking thread, entering the groove 21, as shown in Figure 5, whereupon the spaced points 29 of the shuttle move upwardly and forwardly to enter the loop just above the spreader point 23, the spaced points 29 projecting on opposite sides of the needle. At this 50 55

instant the needle is stationary and the shuttle continues to rotate and the recess 30 therein engages the loop and lifts it upwardly from the needle barb without pulling the thread laterally 5 of the barb which would tend to cut the strands of the thread. The thread moves from the needle over the shuttle, and the bobbin enclosed therein, to form a downwardly facing loop over the bobbin thread, which loop is later pulled down 10 by the take-up mechanism in the horn described later.

By bifurcating the shuttle as described and locating the needle and needle bar intermediate the sides of the shuttle, it is possible to bring the breast of the shoe heel much closer to the needle than has been done previously in this type of machine and hence the sole may be sewed rearwardly of the shank and closer to the heel than has been possible heretofore.

20 The work is fed into position for successive stitches by the mechanism best shown in Figures 8, 9 and 10. A bracket 33 on head 2 fulcrums an offset lever having an upper arm 34 carrying a roller 35 positioned in the groove of the cam 36. 25 The lower arm 37 of the lever is slotted between the lines 38, and a bushing 39 in the slot may be clamped at different positions along arm 37 by the nut 40. A channel member 41 has a stud 42 journaled in bushing 39. An arm 43 is pivoted 30 on the end of head 2 by stud 44 and its upper end carries a block 45 which is slidable in channel member 41.

A feeding lever 46 is pivoted at 47 on the presser foot bar 48 and a link 49 connects the upper ends 35 of arm 43 and lever 46. A feed point 150 is pivoted on the lower end of lever 46, and a spring 151, pulling up on the rear end of feed point 150, thrusts the forward end of the feed point down against the work, or towards the presser foot 152 40 if the work is removed.

A downwardly facing stop element 153 on the lower end of the presser foot bar 48 may engage the rear end of the feed point to limit the upward movement thereof and accordingly limit the 45 downward movement of the front end of the feed point. This prevents the feed point digging into the face of the horn if there is no work in the machine.

The oscillation of lever 34—37 by cam 36 will 50 oscillate the upper end of arm 43 and thereby reciprocate link 49, which in turn reciprocates the feed point 150. As the feed point moves to the right (Figure 9) the forward end rides upwardly over the presser foot 152 and as the feed 55 point moves to the left its spring 151 will thrust the point into the work.

The adjustable mounting of member 41 in lever arm 38 and the sliding engagement of member 38 with block 45 provides means for adjusting the length of the feeding movement of the point 150. If the bushing 39 is moved downwardly it increases the effective length of the lever arm 37 and the length of the movement transmitted to link 49. If the bushing is moved upwardly 60 the opposite result is obtained.

The feeding mechanism comprises a substantial part of the subject matter of a divisional and continuing application, Serial No. 607,305, filed April 25, 1932.

70 A spring 153 normally thrusts the presser foot against the work but the presser foot is positively lifted from the work when the toe 157 of cam 155 engages the roller end of lever 156 and moves the same to tilt its outer end which, with 75 the associated nut and block, forms a well-known

device 154 for gripping and lifting the presser foot bar.

The horn thread L passes upwardly from a spool (not shown) through the wax pot 50 (Figs. 1 and 2) about a tension wheel 51, spans the space between rollers 52 where it is engaged by the thread measuring hook 53, then passes through a hollow tube 54 over the locking roller 55 (Fig. 3) about the upper roller 56, then down and around the take-up roller 57 and then up 10 to the usual whirl (not shown) located in the tip of the horn. The locking lever 58 is pivoted on the horn at 59 and its tip 60 is thrust against the thread on roller 55 by spring 61 on the rod 63 connected to the lower end of lever 58. The 15 tension of the spring is adjusted by the nut 62.

The thread measuring hook 53 is on a shaft 64 having a crank 65 which is oscillated by a bar 66 pivoted on block 67 which is slidable in groove 68 in member 69 which is pivoted at 70 20 to the frame bracket 71 and is oscillated by a cam 72. Rotation of the cam moves member 69 to the left of the position shown in Figure 2 and then to the right, to reciprocate lever bar 66, thereby oscillating shaft 64 and hook 53 to measure the thread for successive stitches.

During this operation, locking lever 58 is functioning to prevent any of the thread in the horn being retracted therefrom instead of being drawn up from the source of supply. To prevent too 30 free a movement of the thread by the measuring mechanism, a tension device is provided including the wheel 51 rotatably mounted on a stationary shaft 91 and about which the thread L is wound one or more times. Wheel 51 is frictionally held against rotation by a collar 92 keyed on shaft 91 and forced against wheel 51 by spring 93. The tension of the spring may be adjusted by the nut 94 threaded on shaft 91. An auxiliary tension device is provided in the horn comprising a pair of spaced rollers 110, journaled on the horn frame, and a movable roller 111 journaled on a lever 112 pivoted at 113 on the horn frame and held by the spring 114 to tension the thread.

Bar 66 extends rearwardly beyond block 67 and 45 at its rear end is connected to the lower end of a vertical rod 74 connected to the rear end of the presser foot release lever 75. Any variations in the thickness of the work will affect the position of lever 75, rod 74, and bar 66 so as to move 50 block 67 in its groove 68 in member 69 and thereby vary the distance which bar 66 will be moved by cam 72 and accordingly the length of thread pulled from the source of supply by hook 53.

The thread lock 58 is released by the take-up 55 lever 76 which is operated by a cam 77 mounted on the main shaft K and engaging one arm of a bell crank 78 pivoted at 79 on the bracket 4. The other arm of the bell crank engages a collar 80 60 slidable on the horn shaft 81 and carrying a bar 82 which is connected at its upper end to a bell-crank 83 (Fig. 3) pivoted at 84 and mounting a block 85 slidable in a groove 86 in take-up lever 76.

As cam 77 tilts bell crank 78 from the position shown, the horizontal arm of the bell crank 78 moves upwardly lifting collar 80, bar 82, and bell-crank 83 which rotates block 85 and lever 76 in an anti-clockwise direction. The surface 87 on lever 76 forms a cam which engages roller 88 on locking lever 58 to move the locking lever tip 60 from the locking roller 55. The take-up roller 57 rises, freeing the upper portion of thread L from tension which permits the thread to be 75

drawn up by the needle and shuttle as previously described.

At the end of the upward movement of the needle and shuttle point the take-up lever 78 begins to descend, whereupon the tension of the work on the upper portion of the thread results in the take-up roller drawing up the slack in the lower portion of the thread which has been provided by the thread measuring mechanism previously described. After this slack has been drawn up, the cam surface 87 releases the locking lever roller 88 and tip 80 again engages the thread on the locking roller 55. Further descent of the take-up lever 78 draws down the slack in the upper portion of the thread and pulls the stitch tight in the work.

The following mechanism provides for manual release of the horn thread and the withdrawal of the work from the machine at any point in the cycle of operation of the machine. An ordinary treadle (not shown) is pivoted to the base of frame 1 and a pull rod 95 (Figs. 1 and 2) extends from the treadle to a lever 96 pivoted on the frame at 97. The rear end of lever 96 has an adjustable stud 98 engaging a shoulder 99 on the rear end of bar 66 whereby depression of the treadle will lift the presser foot.

A shoulder 100 near the forward end of lever 96 engages a stud 101 on the outer end of a lever 102 pivoted at 103. The forward end of lever 102 engages a block 110 on the lower end of tube 54 which is arranged to engage the underside of a lug 104 (Fig. 3) on locking lever 58 to lift the latter from thread locking position as shown in Figure 3.

At the same time the thread tension is released by rod 95, operating through a lever 105 pivoted at 106 with its forward end adapted to engage the lower portion of a yoke 107 pivoted on a depending bracket 108 and having studs 109 engaging the rear flange on collar 92 whereby the latter may be moved against the pressure of spring 93 to relieve the tension wheel 51 of friction. The thread take-up, lock and measuring mechanism comprise the subject matter of a divisional application, Serial No. 620,660, filed July 2, 1932.

The various detail mechanisms described above cooperate to produce a lock stitch machine which operates satisfactorily, having reference particularly to the attainment of the objects set forth at the beginning of this specification. Obviously, many features may be used in stitchers other than the McKay type and some features may be omitted in McKay or other stitchers without negativating the use of other features, and all of the details may be varied without departing from the spirit of my invention, and I contemplate the exclusive use of all modifications of the described structure coming within the scope of my claims.

What is claimed is:

1. In a machine of the class described, a drum-like shuttle with its axis disposed horizontally, a bobbin within said shuttle, the sides of the shuttle projecting radially a substantial distance beyond the edge of said bobbin, and a vertically reciprocating structure comprising a needle and needle bar positioned to pass between said shuttle sides and adjacent to the periphery of said bobbin, a portion of said structure remaining between the sides of said shuttle throughout the cycle of operations of the machine.

2. In a machine of the class described, a vertically reciprocating needle, a horn below the same, means for supplying a thread loop through

said horn to the point of said needle to be drawn upwardly by the latter, a spreader element having a point arranged to be projected between the strands of said loop transversely of the path of the needle and below the point of the latter as it is raised and then withdrawn, and a drum-like shuttle with its axis disposed horizontally and its periphery bifurcated circumferentially to receive the needle and recessed transversely to form a hook with spaced points arranged to be projected into the path of the needle point and above said spreader so as to engage the looped thread and carry it over the body of the shuttle.

3. A stitcher drum-like shuttle having a circular periphery for engaging a supporting bearing, said periphery having a circumferential groove for receiving the point of a needle, a bobbin and a bobbin case within said shuttle, the sides of said shuttle projecting radially beyond the edge of said bobbin case, the peripheral walls of said shuttle and case each being removed at least in part throughout an arcuate portion to provide for the passage of a needle adjacent to said bobbin case.

4. In a machine of the class described, a drum-like shuttle having a circumferential groove in its periphery, a needle reciprocating in said groove, and a thread loop spreader member having a point projected at intervals below the point of said needle and into said groove.

5. A structure as set forth in claim 4 in which there is a transverse recess in said drum periphery forming a hook with spaced points for engaging the thread loop opened by said spreader and carrying the same over the shuttle.

6. In combination, a stitcher drum-like shuttle, a drum-like bobbin case within said shuttle and a bobbin in said case, a portion of the peripheral wall of said shuttle being cut away and the adjacent portion of the peripheral wall of said bobbin case being grooved to provide for the passage of a needle bar immediately adjacent to the edge of said bobbin.

7. In a machine of the class described, a shuttle oscillating about its axis and having a peripheral groove, and a needle reciprocating in said groove, said shuttle having a transverse recess extending inwardly from its periphery and, with said groove, forming a split hook for entering the loop of a thread engaged by said needle, the inner end of said recess engaging the loop of said thread and moving it away from the needle bar in a direction parallel with the needle axis and then carrying the thread over the shuttle.

8. In a machine of the class described, a shuttle oscillating about its axis and having a transverse recess forming a thread engaging hook and also having a peripheral groove bifurcating said hook in a plane transverse to said axis, and a needle reciprocating in said groove.

9. In a machine of the class described, a work support, means for feeding a lower thread upwardly therethrough, a hook needle mounted above said work support and descending through the same to engage said thread, an oscillating shuttle journaled above said work support and serving to take the loop of said lower thread, formed by said needle from the same while said needle is moving upwardly, and a bobbin for an upper thread in said shuttle, said needle reciprocating in a plane intermediate the planes of the sides of said bobbin.

10. In a machine of the class described, a drum-like shuttle having a peripheral groove, a reciprocating hook needle extending into said groove

- and forming a thread loop upon its upward movement, said shuttle having a loop taking point, and means actuating said shuttle and needle so that while said needle is moving upwardly and while its hook is in said groove said point overtakes said hook in its upward movement to lift the loop from said hook and then moves rearwardly from the hook to pass the loop over the body of the shuttle.
11. In a machine of the class described, a work support, means for feeding a lower thread upwardly therethrough, a shuttle having a circular periphery for engaging a circular bearing, said shuttle oscillating about its axis and having a peripheral groove, a bobbin case in said shuttle, and structure comprising a needle and needle bar
- reciprocating in said groove in a line exterior of said case and including a hook descending past said shuttle to engage said thread.
12. In a machine of the class described, a shoe supporting horn, a vertically reciprocating structure comprising a needle and needle bar arranged to descend into an opening in the top of said horn and to ascend above the same, and an oscillating drum-like shuttle with its axis disposed horizontally and with a portion of its periphery adjacent said structure and with the planes of its sides being located on opposite sides of said structure, said periphery being grooved and at least some part of said structure being in said groove throughout the cycle of movement of said shuttle. 15

EUGENE G. WOLF.
